SHOULDER STRAP HOLDER

Florence M. Stader, Plymouth, Mich.

Application May 23, 1934, Serial No. 727,176

8 Claims. (Cl. 24—73)

The invention relates to garment holding devices and refers more particularly to devices for holding in place the shoulder straps of inner garments relative to outer garments.

One of the objects of the invention is to provide an improved holding device which is so constructed that a shoulder strap will readily and automatically engage the device. Another object is to so form the device that it may be easily secured to the outer garment. A further object is to form the device of a continuous length of wire and in such a manner that the device may be economically manufactured.

These and other objects of the invention will become apparent from the following description, taken in connection with the accompanying drawing, in which

Figure 1 is a perspective view with a portion of the outer garment broken away illustrating a holding device embodying my invention in place;

Figure 2 is a perspective view of the holding device;

Figure 3 is a cross section on the line 3—3 of Figure 2;

Figure 4 is a view similar to Figure 2 illustrating another embodiment of my invention.

The holding device, as illustrated, is adapted to receive and hold in place the shoulder strap 1 of the inner garment 2 relative to the outer garment 3. This device is a clasp formed of a continuous length of wire and having the upper portion 4 for securing to the shoulder portion of the outer garment and the lower portion 5 for receiving the shoulder strap.

The lower portion comprises the upper bar 6 and the lower bar 7, both of which extend in the same general direction and together form a generally U-shaped portion opening toward the neck of the wearer of the garments. The bars 6 and 7 are connected preferably by the eye 8 and the bar 7 is return-bent at its free end to form the eye 9. This eye is circular and extends toward the bar 6 and is spaced therefrom. The eye 9 has its end 10 extending into close proximity to the bar 7 and also has the portion 11 which is spaced from the bar 7 and is located inwardly beyond its end 10, this portion being adapted to extend over the shoulder strap when the latter engages the bar 7 to thereby retain the shoulder strap from accidental disengagement.

The upper portion 4 is in the nature of a loop which is elongated in a direction approximately parallel with the upper bar 6. This loop is formed at the free end of the upper bar 6 and has the upper bar 12 and the lower bar 13 which are ap-

proximately parallel. The lower bar extends approximately parallel to the upper bar 6 and is slightly spaced therefrom and preferably laterally offset. This bar 13 has the pointed end 14. The construction is such that the bar 13 may be passed through the shoulder portion of the outer garment and preferably the shoulder seam so that the upper bar 12 of the loop engages the outer garment and carries the holding device. The holding device is secured to the outer garment so that the U-shaped portion 5 opens toward the neck of the wearer, as shown particularly in Figure 1. It will also be noted that this lower portion extends closely adjacent the shoulder of the wearer so that the shoulder strap will automatically become engaged with the lower bar 7 or, if desired, may be readily inserted into place.

The holding device illustrated in Figure 4 is a clasp formed of a continuous length of wire having the lower portion 15 formed in the same manner as the lower portion 5 of Figures 1, 2 and 3. Its upper portion 16 differs in that it is in the nature of the bar 17 connecting into the free end of the upper bar 18 of the lower portion 15 and located in substantially the plane of this upper bar. The bar 17 terminates at its free end in the eye 19, the portion 20 of the bar adjacent the eye being preferably inclined toward the upper bar 18. The device is secured to the shoulder portion of the outer garment by sewing the bar 17 to the shoulder portion and the construction of the bar is such that it provides for effectively securing the same.

From the above description, it will be readily seen that I have provided a simple construction of holding device which is formed of a continuous length of wire and in such a manner that the holding device may be manufactured at relatively low cost. It will also be seen that the holding device may be readily secured to the outer garment and that the shoulder strap of the inner garment may be readily secured to the holding device and effectively retained in place. It will be further seen that the holding device will effectively retain from relative displacement both the outer garment and the shoulder strap.

What I claim as my invention is:

1. A device for holding a shoulder strap of an inner garment relative to an outer garment, comprising a clasp having a portion for securing to the outer garment, a bar connected to said portion, and a second bar connected to said first mentioned bar and forming therewith a generally U-shaped portion opening toward the neck of the wearer of the garments and adapted to auto-

- 5 matically receive the shoulder strap, said second bar terminating in an eye extending toward said first mentioned bar and spaced therefrom, said eye having a portion spaced from said second bar and adapted to extend partially over the shoulder strap to retain the same.
- 10 2. A device for holding a shoulder strap of an inner garment relative to an outer garment, comprising a clasp having a portion for securement to the outer garment, a bar connected to said portion, and a second bar connected to said first mentioned bar and forming therewith a generally U-shaped portion opening toward the neck of the wearer of the garments and adapted to automatically receive the shoulder strap, said second bar being return-bent at its free end to form an eye extending toward said first mentioned bar, said eye being spaced from said first mentioned bar and having its end extending into close proximity to said second bar and a portion spaced from said second bar located inwardly beyond its end to retain the shoulder strap.
- 15 3. A device for holding the shoulder strap of an inner garment relative to an outer garment, comprising a clasp having a lower portion for holding the shoulder strap and an upper loop provided with a lower pointed bar, said loop being adapted to be detachably pinned to the outer garment by passing said lower pointed bar through the outer garment.
- 20 4. A device for holding the shoulder strap of an inner garment relative to an outer garment, comprising a clasp having a lower bar for engaging and holding the shoulder strap, a second bar above said lower bar and connected to and extending in the same general direction as said first mentioned bar, and an upper loop connected to said second bar and provided with a lower

5 pointed portion extending adjacent to said second bar, said lower pointed portion being insertable through the outer garment whereby said clasp may be detachably pinned to the outer garment.

10 5. A garment holding device formed of a continuous length of wire having a lower bar terminating in an eye, a second bar above said lower bar and connected to and extending in the same general direction as said first mentioned bar and in spaced relation to said eye, and a loop connected to said second bar and provided with a lower pointed bar extending approximately parallel to said second bar.

15 6. A fastener, comprising a portion for attachment to an article, a bar connected to said portion, and a loop extending from said bar and elongated in the same general direction as said bar, said loop being provided with a bar extending approximately parallel to said first mentioned bar and having a pointed end.

20 7. A garment holding device formed of a continuous length of wire bent upon itself to provide a pair of bars extending in the same general direction and spaced from each other, one 25 of said bars terminating in a transverse portion extending toward the other of said bars, and a loop upon the other of said bars elongated in the same general direction as the said other of said bars and provided with a bar extending approximately parallel to the said other of said bars and having a pointed end.

25 8. A fastener formed of a continuous length of wire having a generally U-shaped portion for attachment to an article and an integral loop 30 provided with portions overlying each other and extending in the same general direction, one of said portions terminating in a pointed end.
